LAUNDRY DRIER

George D. Chadeayne, Brooklyn, N. Y.

Application July 3, 1935, Serial No. 29,611

3 Claims. (Cl. 34—40)

My present invention relates to laundry driers particularly adapted for domestic use. It is the principal object of my invention to simplify and improve existing types of such driers to increase the efficiency of same. More specifically, it is an object of the invention to provide a laundry drier for domestic use utilizing low pressure steam, as for example that used in the heating systems of apartment houses. Further objects to be attained and advantages of the invention will be apparent as the description proceeds and the novel features will be pointed out in the claims.

The invention will be best understood by reference to the following detailed description taken 15 with the annexed drawings, in which

Figure 1 is a view in vertical longitudinal section of a preferred embodiment;

Figure 2 is an end elevational view as seen to the right of Figure 1; and

Figure 3 is a section taken on the line 3—3 of Figure 1.

Referring to Figure 1, 10 denotes generally a clothes supporting rack consisting of horizontally disposed rods 11, 12, 13, 14, etc., which extend 25 from a perforate rear framework 18 to an imperforate front wall 18a. As seen best in Figures 2 and 3, the frame is preferably not very wide in relation to its height or depth so as to permit ready access to the rods, thereby facilitating the 30 putting in and taking out of the clothes. The racks 10 are contained within a housing 19 from which the racks may be drawn out to the position shown in dotted lines in Figure 1. To permit this, the following arrangement of parts may be provided: Supported in said housing is a pair of channel beams 20, 20, one support for which, 21, is shown to the right of Figure 1. Journaled in 35 said supports 21 is a grooved roll 22. In the groove of this roll rides a rail 23 from which the rack is supported by means of a tie member 24, at the right of Figure 1, and a bracket 25 at the left thereof. At the junction of the bracket 25 and the rail 23 is journaled a pair of rolls 26 which travel within the channel beams 20, 20. 40 Bracket 25, by virtue of its horizontal displacement to the left of the rack 10, Figure 1, provides sufficient leverage to support the rack in its drawn-out position in which the rolls 26 approach the grooved roller 22.

Bracket 25 is attached to framework 18 by means of bolts 30 and 31, Figure 3, there being provided for the latter a plate 32, attached to framework 18, having intersecting a slot 33 by means of which the framework can be accurately 45 suspended by means of bolt 34.

A localized source of heat is provided preferably in the form of a steam coil 35 connected with a source of steam, not shown, the coils preferably being provided with fins 36 for increasing radiation. Beneath the coil 35 is disposed a fan 37 driven by a motor 38, a suitable casing 40 being provided around the fan and coil to prevent air slippage from the fan and to direct the air over the coil. The inlet side of the fan communicates with air duct 42 for the recirculated air through 10 the apertured support 43. Said inlet also communicates with the outside atmosphere through aperture 44 provided with a slide 45 by means of which the volume of fresh air admitted may be regulated.

It is a feature of the invention to distribute the air more or less uniformly over the clothes and to this end a baffle 47 is provided having apertures 48, Figures 1 and 3, at spaced intervals to direct the air in somewhat horizontal streams. 20 Said baffle is also inclined or otherwise disposed so as to provide with the walls of the chamber a conduit having a decreased cross section as the distance from the coil 35 increases so as to assist in maintaining a uniform air supply throughout 25 the drying compartment. The air thus set in circulation passes over the clothes to be dried in streams apportioned to the zones defined by the rods 11, etc., and more or less parallel to the plane 30 of the clothes whereby a maximum surface of the clothes is presented to the air stream and circulation of the air is facilitated. The air is collected in the down draught space 50 rearward of the rack 10, some of the air passing downwardly through the screen 51 at the bottom of the rack. 35 A portion of the air is permitted to escape from the chamber through perforate frame 18 to a perforated pipe 55, the withdrawn air being made up by fresh air admitted through the apertured plate 44. When the clothes are dried the rack is 40 withdrawn by pulling same outwardly by means of the handle 57 to the position shown in dotted lines in Figure 1, whereupon the dried clothes are removed and, if desired, a new batch of wet clothes is again hung on the rack.

It will be noted that by re-using the heated air until it is saturated with water vapor, a maximum utilization of the heat results. Furthermore, by leading the air in streams more or less parallel to the plane of the clothes, a minimum of 50 resistance to the air flow takes place while affording ample contact with the clothes. By virtue of the improved construction, steam at a low pressure, as for example under ten pounds, may be used.

Various changes may be made in the embodiments specifically described in detail without departing from the spirit of my invention or the scope of the appended claims. Especially may 5 the means for holding the clothes be varied while preserving the principle of drying herein set forth.

I claim:

1. A laundry drier having a rack containing 10 a plurality of substantially horizontally disposed clothes supporting members, a housing therefor, said rack being capable of being moved to a withdrawn position from said housing but constituting therewith in closed position a substantially closed chamber, a localized source of heat comprising a steam coil at the front end of said housing and disposed adjacent the bottom thereof, a fan for circulating air upward through the coil and a substantially upright 15 baffle carried by the front end of said rack and disposed directly over said coil when said rack is closed, said baffle serving for directing the air so heated from the coil and apportioning same to zones defined by said clothes supports and in 20 vertical planes parallel with said supports, and said housing having a foraminous false bottom acting to direct at least a portion of the moisture laden air downward, whence it finds its way forward beneath said false bottom toward 25

said heater and fan for recirculation, means for venting at least a portion of the vapor laden air, and means for admitting fresh air.

2. A laundry drier having a rack containing a plurality of substantially horizontally disposed 5 clothes supporting members, a housing therefor, said rack being capable of being moved to a withdrawn position from said housing but constituting therewith in closed position a substantially closed chamber, a localized source of heat 10 disposed at the front end of said housing and disposed adjacent the bottom thereof, a blower means for circulating air upward over said source, thereby heating and creating an upward stream of said air, and an upright, inclined, ap- 15 ertured baffle carried by said rack for directing the air so heated from said source and for causing a differential apportionment of same to zones defined by said clothes supports and in vertical planes parallel with said supports, and means 20 for returning at least a portion of the air for recirculation by said blower means, means for venting at least a portion of the vapor laden air, and a means for admitting fresh air.

3. The drier according to claim 2 including 25 means for regulating the amount of fresh air added.

GEORGE D. CHADEAYNE.
